UNITED STATES PATENT OFFICE

2,484,378

DEVELOPING TANK FOR DEVELOPING
PHOTOGRAPHIC FILMS

Samuel Freeman, New York, N. Y.

Application January 19, 1945, Serial No. 573,599

2 Claims. (Cl. 95—90.5)

1

My invention relates to a new and improved developing tank for developing photographic films.

One of the objects of my invention is to improve the tank which is disclosed in U. S. Patent No. 2,214,581 which was issued to me on September 10, 1940.

In addition to having the advantages described in said U. S. Patent No. 2,214,581, the improved device automatically separates the protective paper from the film by merely turning the holding spool on which the film and protective paper are spirally wound, thus making it unnecessary to pull the end of the protective paper which projects out of the tank.

In addition, the improved device permits the ready separation from the film, of the end-portion of the protective paper which is adherently connected to the film. This eliminates the possibility of tearing or rupturing the strip of protective paper, if its end-portion adheres tightly to the film. Such tight adherence can occur especially in cold weather.

Other objects of my invention are to provide a device which is more simple and reliable to construct and to operate.

Numerous additional important objects and advantages of my invention will be stated in the annexed description and drawings which illustrate preferred embodiments thereof.

Fig. 1 is a top plan view of the improved device, with the cover removed.

Fig. 2 is a vertical elevation, partially in section, of the improved device, showing the cover in its operative position.

Fig. 3 is a top plan view of the cover, detached from the casing.

Fig. 4 is a sectional view on the line 4—4 of Fig. 3.

Fig. 5 is a bottom plan view of the hood which is provided for the holder of the knife.

Fig. 6 is a detail sectional view which illustrates the loading of the holder with the film.

Fig. 7 is a detail elevation which shows the means for clamping the roll of film and paper within the holder.

Fig. 8 is a sectional view on the line 8—8 of Fig. 7. This shows, in broken lines, the position of the film-spool, when it has been fully unloaded.

Fig. 9 is a bottom plan view of a modification of the cover which is shown in Fig. 3.

Fig. 10 is a detail sectional view, showing the means for holding certain members in their respective adjusted positions relative to their shafts.

Fig. 11 is a detail section, which shows that the

protective paper is led from the holding spool to the outlet channel in a curved path, whereas, in the embodiment of Fig. 2, the protective paper is led to the outlet channel from the holding spool, over the respective edge of the slit of the holder, in an upward vertical path.

Fig. 12 is a sectional view which illustrates a modification, in which each wall of the outlet channel for the protective paper, is provided with a liner which is made of either soft or flexible filamentous material, in order to provide a seal against the admission of light.

Fig. 13 shows a modification of the holder, for guiding films of different respective widths, into the guides which guide the film into the take-up spools.

The device comprises a tank 1 which can be made of any suitable material which is inert to the developing solution. A shaft 2 is journaled in suitable bearings which are provided in the front and rear walls of said tank 1. As in said previously issued patent, respective take-up spools 3 are adjustably fixed to the shaft 2. These take-up spools 3 can be moved along the shaft 2, for taking up films of different widths. When the adjustment of spools 3 has been made, said spools 3 are then clamped or otherwise secured to shaft 2. The walls of said spools 3, which face each other, are provided respectively with spiral grooves G, as in said previously issued patent. Each respective spiral groove G of each spool 3, has an inlet end which is close to the center of the respective spool 3.

As shown in Fig. 1 and Fig. 2, a gear 4 is fixed to the respective adjacent spool 3. The gear 4 may be made integral with the respective spool 3. The shaft 2 and the two spools 3 and the gear 4 turn in unison.

A rod 5 is turnably mounted in respective recesses of the front and rear walls of the tank 1. Said recesses are open at their tops, so that the rod 5 can be lifted out of said recesses. Respective film-guides 6 are fixed detachably and adjustably to the rod 5. Each said film-guide 6 comprises parallel arms 6a and 6b which are integral with a respective flange 7. The arms 6a and 6b are parallel to each other, and they are wholly separated from each other, except where each pair of said arms is united with the respective flanges 7.

Each said flange 7 has an internal guide-wall 7a. These internal walls 7a are inclined transversely towards each other, in order transversely to arch the film between the narrowest portion of the film-guide, which is provided by said internal guide-walls 7a.

The grooves **G** in the proximate faces of the spools **3** are of sufficient depth, so that the film is not transversely arched when it is located in said grooves **G**. Since the film is resilient, its temporary transverse arching between the internal guide-walls **1a**, causes the film to spread transversely into the grooves **G** without transversely arching said film, thus reliably seating the edges of the film in non-arched shape in the grooves **G**. Each said guide **6** is provided with a hollow hub **8** in which the rod **5** is seated. As shown in Fig. 10, the rod **5** is provided with a rib which is seated in a corresponding recess of the respective hub **8**, so that the rod **5** and the hubs **8** turn in unison. Each hub **8** is transversely adjustable along the rod **5**. This enables the device to receive films of different widths. After the guides **6** have been thus transversely adjusted, their respective hubs **8** are held in adjusted position, by means of detachable tapered pins **9**, which have tight fits in correspondingly aligned bores of the hub **8** and the rod **5**.

As in U. S. Patent No. 2,214,581, a flexible pull member **10** has its lower end fixed to the shaft **2**, so that the flexible pull member **10** is wound spirally around the shaft **2**, when said shaft is turned in the proper direction. A clamp **11** is fixed to the outer end of the flexible pull member **10**. This clamp **11** can be detachably fixed to the end of the roll of film which is to be developed. Ordinarily, said end of the roll of film has a paper strip to which said clamp **11** can be fixed.

As shown in Fig. 2, the tank **1** is provided with an external compartment **12**. The loader **14** is turnably mounted in said compartment **12**. This loader **14** is of general cylindrical shape. Said loader has a longitudinal slit whose edges are defined by the edge-walls **15** and **16**. One end of said loader **14** is open, so that the roll of film can be inserted longitudinally into said loader **14**. One end of said loader **14** is closed, and said closed end is provided with an operating knob **17**, which is located externally and in front of the front wall of the compartment **12**, when the loader **14** is located in operative position. The end wall **18** of said compartment **12** is closed. The closed end of the loader **14** is provided with a flange **19**, which fits snugly and light-tight in the open front wall of the compartment **12**, when the loader **14** is in position.

Adjacent the knob **17**, the hub of a latch **20** is turnably mounted upon a stud of the loader **14**. The knob **17** prevents the hub of latch **20** from slipping off holder **14**. As shown in Fig. 3, the cover **21** is provided with a half-cylindrical flange **22**. The latch **20** is provided with an inwardly bent hook-end **23**, which can be moved over the half-cylindrical flange **22**, so that the latch **20** then detachably locks the cover **21** in light-tight position on the tank **1**.

A clamping frame **25** is located in the loader **14**. Said clamping frame **25** comprises a base **24** which is of general trough or half-cylindrical shape.

The spirally wound mass of film and protective paper, which is located on its holding-spool **30**, always frictionally abuts the base **24**. When the holding-spool **30** is empty, said holding-spool abuts said base **24**. The disc flanges **31** of the holding-spool never contact with the base **24**, save possibly at the inner end-faces of said flanges **31**.

Respective disks **26** are fixed to the base-sections **24a** and **24b** of base **24**. Each disk **26** is provided with a through-and-through slot **27**. In

this illustrative embodiment, each said slot **27** is eccentric relative to the respective center of the respective disk **26**. This is an optional feature, because the longitudinal walls of said slot **27** can be disposed symmetrically, relative to a respective diameter of the disk **26**.

The respective slots **27** of the respective disks **26** are parallel to and aligned with each other.

A shaft **28** is turnably mounted in suitable bearings which are provided in the disks **26**. A torsion spring **29** is coiled around said shaft **28**. One end of the torsion spring **29** is fixed to the shaft **28**. The other end **29a** of the spring **29** abuts the base-section **24a**.

15 The spiral roll of film and paper is wound upon the usual cylindrical holding-spool **30**, which has the usual enlarged disc-shaped flanges **31**. Said holding spool **30** has a bore, in which a rod **32** is located. This rod **32** extends through the respective slots **27**. Respective clamping rods **33** are fixed to the shaft **28**.

When the rod **32** is in operative position, the torsion spring **29** biases the clamping rods **33** to press against the respective exposed end-portions of the rod **32**, so that said rod **32** is forced towards the sections of the base **24**, thus firmly pressing the outermost layer of the spirally wound roll of film and paper which is wound upon the spool **30**, against the base sections **24a** and **24b**.

30 As shown in Fig. 7, each disk **26** is connected to its respective base-section **24a** or **24b**, by a U-shaped member, thus providing a space into which the respective flanges **31** can extend.

The pressure of the clamping rods **33** is maintained by spring **29**, so that a part of the periphery of the spirally wound roll of film and paper **F, P** on the spool **30**, is always pressed against the base-sections **24a** and **24b**. This provides frictional retarding means for retarding the unwinding of the material from the spool **30**, thus insuring even and uniform unwinding. As the film **F** and paper **P** are unwound from the holding spool **30**, its flanges **31** continue further to enter the spaces between the disks **26** and the base-sections **24a** and **24b**, until said flanges **31** are finally in the positions shown in broken lines in Fig. 8. The empty holding spool **30** now contacts with, and it is pressed against, the base-sections **24a** and **24b**, between the flanges **31**.

35 The entire frame **25**, together with the spool on which the combined roll of film and paper is wound, can be slid longitudinally into the loader **14**, through the open end-face of said holder. The disks **26** can fit tightly enough in the loader **14**, so that the frame **25** and the loader **14** turn in unison. If desired, a conventional key or the like can be provided in order to insure the simultaneous rotation of the frame **25** and the loader **14**. The holding-spool **30** can turn relative to frame **25** and loader **14**.

40 One disk **26** is provided with a stop **34**. Therefore, when the rod **32** is detached from the frame **25**, in order to locate the spool **30** in the base **24**, the movement of the arms **33** is limited by said stop **34**, thus preventing the unwinding of the torsion spring **29**. In order to provide adjustment for films of different widths, the base **24** is preferably, but not necessarily, made of said two separate sections **24a** and **24b**. Each of these sections is provided at each of its edges with an eye **35**. The eyes **35** of base-section **24a** are slidable on respective rods **36**. At the bottom of each section **24a** and **24b**, an additional eye **37** is provided. The section **24b**, which is fixed to the respective disk **26**, has its edge-eyes **35** and its bot-

tom eye 31, fixed to the respective three rods 36. The three corresponding loops of section 24a, are 5 slidable on the respective rods 36.

The two top rods 36 are detachably fixed to one of the disks 26. Said respective disk 26 is at the right of Fig. 7. For this purpose, each said top rod 36 is provided with an external thread 38. Lock nuts 39 are provided for detachably fixing each top rod 36 to the respective disk 26. The bottom rod 36 is not fixed to either disk 26. It 10 is merely clamped to the bottom loop or eye 31 of section 24b.

The method of using the device is the same as the method described in said U. S. Patent No. 2,214,581. As described in said patent, a pull-strip is fixed to the outer end of the roll of film, and the inner end of the roll of film is fixed adhesively to the protective paper P, by a fastening strip which is made of cloth or paper.

Fig. 2 shows the initial position of the loader 14, after it has been loaded with the spool 30 and the combined film and protective paper F, P which is wound on said spool 30. In said position, edge-wall 16 of the slit of loader 14, is substantially vertically aligned with the axis of said loader 14.

While the loader 14 is located in its initial loading position as shown in Fig. 2, the film F and the protective paper P are unwound from spool 30, by pulling upon the outer free end of the protective paper P, until the pull-strip is exposed.

The length of the unwound protective paper P is sufficient at this point, so that the unwound end-portion of said paper P can be led over the flange 41, compartment 12, so that the free edge of said protective paper P is located below the bottom of flange 41.

The loader 14 is now turned counterclockwise from the position shown in Fig. 2. The top wall of shoulder 44 of the loader 14, thus clamps the protective paper P and the pull-strip, against the 40 respective internal wall of compartment 12. The clamp 11 is now fastened to the end of the pull-strip.

The loader 14 can be detachably locked in the position in which paper P and the pull-strip are 45 thus clamped, by means of a pin 54, which is downwardly biased by a spring 55. The tip of pin 54 enters a transverse groove of loader 14. This groove has outwardly inclined walls, so that said groove can be released from the pin 54, by exerting sufficient turning force upon the holder in the clockwise direction, by means of knob 47. This prevents the loader 14 from turning accidentally out of its said clamping position, while the clamp 11 is fastened to the pull-strip.

The cover 21 is applied and latched, while the loader 14 is in said clamping position.

The loader 14 is then turned clockwise back to the position shown in Fig. 2, which is now an unwinding position, until its shoulder 44 abuts a corresponding internal flange of the inner wall of compartment 12.

The protective paper P is now located in and below the outer bottom end of channel 43, which is between the wall 40 of flange 41, and a corresponding flange 42 of cover 21. The protective paper P either forms a light-tight filling in said channel 43, or if not, the curved shape of said channel 43 and of the paper P therein prevents the entry of light.

After the cover has been thus located and locked, and the pull-strip has been fixed to clamp 11, the shaft 2 is rotated by rotating a knob 45, which is detachably fixed to a shaft 46 which is journaled in suitable bearings which are pro-

vided in the cover 21. A gear 47 is fixed to said shaft 46. When the cover 21 is located in operative position, gear 47 meshes with gear 4. Therefore, by turning the knob 45 counterclockwise, the gear 4 and the shaft 2 will be turned clockwise, thus pulling the film F off the spool 30, and winding the film F spirally in the grooves G of the spools 3.

The gears 4 and 47 make it unnecessary to extend the shaft 2 through the wall of the tank, thus eliminating leakage of the developing solution. The shaft 2 is located wholly within the tank. By using said gears, it is possible to fill the tank with developing solution, to the top of gear 4. Hence all the film which is located in the grooves G of the take-up spools, is immersed in the developing solution. When the film is thus taken up in said grooves G, wholly separated from the protective paper P, a few turns of said take-up spools 3 will eliminate air-bubbles which cling to the film. If the take-up shaft 2 extends through a wall of the tank, it is practically impossible to provide the shaft 2 with a leak-proof bearing. Hence, if the gears 4 and 47 are omitted, without the substitution of an equivalent, the tank can be filled with developing solution, only up to the take-up shaft 2. In such case, the upper half of the film in grooves G is above the developing solution. It is then necessary to turn the shaft 2 at frequent intervals during the developing period to eliminate air bubbles, as such air bubbles spot the film. Likewise, if only part of the film is immersed in the developing solution, the take-up shaft 2 must be turned at frequent intervals, in order to secure proper uniform development.

While the film is thus being unwound, the protective paper P is simultaneously unwound and fed outwardly through the channel 43. The protective paper P has natural resilience, and it is unwound in a direction opposite to the curl or set which is imparted to said resilient paper P, by the winding of said paper, together with the film, upon the spool 30.

Therefore, said protective paper P has sufficient stiffness so that it can be fed automatically through the space 43 by turning spool 30 by means of pull-member 10, without pulling the paper P manually. For this purpose, the walls of the channel 43 are curved in order to permit an easy and reliable movement of the paper P through the channel 43.

While the spool 30 is being turned so as to unwind the film and protective paper therefrom, the loader 14 is held in the position shown in Fig. 2, because the unwinding pull on the film urges the loader 14 to turn clockwise. The protective paper P is led over the edge wall 16 of the slit during the unwinding, upwardly in a substantially vertical direction, and through the channel 43. There is little or no bend of the protective paper P, over the edge wall 16, thus minimizing friction, so that the stiffness of the paper P is sufficient to push the paper P through the channel 43, without pulling the exposed portion of the paper.

Likewise, the channel 43 is of sufficient depth in relation to the thickness of paper P, so that the paper P can slide easily through channel 43. The guide 53, which is fixed to cover 21, aids in deflecting the upwardly moving protective paper P, into the channel 43. The bottom face of guide 53 is shaped substantially as a continuation of the inner wall of flange 42, which constitutes one of the walls of channel 43.

The invention is not limited to any particular

configuration of the walls of the channel 43, as long as said configuration permits the automatic feeding of the paper through said space 43.

After the film has been wholly wound into the grooves G, it is necessary to cut off the inner end of the strip of paper P, or to sever the fastening strip. As an alternative, the inner end-portion of the film F can be severed.

For this purpose, I use a knife 48 which is transversely slidable in a slot 57 of cover 21. Said knife 48 is fixed to slide-rod 49 which is laterally slidable in a tube 50 which is fixed to a hood or enlargement 51 of the cover 21. A knob 52 is fixed to one end of the slide-rod 49. The tube 50 has an externally threaded end which projects in front of the cover 21. The internal wall of said knob 52 is tapped so that said knob 52 can be detachably locked to the respective end of the tube 50. The knob 52 is turnable on the slide-rod 49, and it is held against slipping off the slide-rod 49.

The knife 48 clears the film, when knob 52 is detachably locked to tube 50.

Instead of using the rod 5 and film-guides 6, I can use the rod 5a which is fixed to the wall of the cover 21, in any suitable manner. Said rod 5a may be integral with the cover 21. I can replace the film guides 6 by corresponding guides 55 which are adjustably fixed to the rod 5a, by means of clamping screws 56.

The guides 55 can be molded integrally with the cover 21, either with or without the rod 5a, thus greatly lowering the cost of manufacture of the complete device. In such case, the guides 55 are not adjustable relative to each other.

The clamping frame 25 is an optional feature.

Numerous changes and omissions and additions can be made in the foregoing, without departing from the scope of my invention.

In one aspect of my invention, it includes a tank which has a solution-holding compartment; means located in said compartment for taking up the film in spirally wound form, with the layers of the film separated from each other; a holder which is turnably associated with said tank, spaced from the developing-solution, said holder holding the film-spool on which the film and protective paper are spirally wound. Said tank has a cover, said cover and said tank having walls which define a channel through which the protective paper can be slid, in a direction reverse to the direction in which the film is unwound from its holding spool; said channel being shaped so that the protective paper can be forced through the same, solely by the force which is exerted on said protective paper by the unwinding of the film from the holding-spool.

This is per se a feature of my invention, irrespective of other elements of construction.

The adjacent walls of channel 43 are made of material which has a black or other dark color, so as to have minimum reflecting power. Said adjacent walls may be smooth. As an alternative, said adjacent walls may have rough surfaces, in order to reflect the light in all directions. Hence, even if there is no protective paper in channel 43, no light can enter through said channel to fall upon the film which is being developed, because the light which enters channel 43 is absorbed by its walls. For this purpose, the channel 43 is made of minimum depth, just enough to permit the paper P to slide through said channel.

The width of the paper P is preferably equal to the width of channel 43, but the paper may be of less width than said channel. The invention is 75

not limited to the convex shape of the channel 43 which is disclosed as an illustration. It includes a channel 43 of any gradual contour, which excludes the light when the protective paper P is located therein. By a gradual contour, I define a contour which is sufficiently free from a sharp bend or bends, which would bend the protective paper P in said channel 43, so as to require a pulling force on said protective paper P, externally to the tank, in order to move the protective paper P through said channel. By eliminating such sharp bend or bends, I can move the protective paper P through said channel 43, solely by the pushing force which is exerted by the spool 30, when said spool is turned, in order to unwind the film and protective paper from said spool 30.

The invention is not limited to a tank device in which the walls of channel 43 are respective walls of the cover and of the tank. That is, in one aspect of the invention, the cover 21 can be considered as being part of the tank device, when the tank device is ready for operation, and while the film is being developed.

Fig. 11 shows the path of the paper P, in broken lines, from the take-up spool which is located within the holder 14, to the channel 43. In this embodiment, the paper P is led over the respective edge of the slit of holder 14, to the inner end 30 of channel 43, in a curved path. In this embodiment, the optional deflector 53 is integral with cover 21, although these parts may be non-integral. The concave bottom wall of deflector 53 is shaped so that its edge 53a, and a part of said 35 concave bottom wall which directly precedes said edge 53a, is below the top of wall 40, thus providing additional protection against the entry of light. Said concave bottom wall of deflector 53 is also colored so that it has minimum reflecting power.

Fig. 12 shows an optional feature whereby each wall of channel 43 has a liner 43a fixed thereto. Each liner 43a is made of light-absorbent material. Said material can be soft and flexible and compressible. It may be made of any black pile fabric or filamentous fabric. The adjacent walls or filaments of said liners 43a normally contact with each other, in order to provide a seal against the entry of light. The protective paper P can slide easily between said liners 43a, with very little friction. The thickness of paper P may be about 0.004 inch, as an example. In this embodiment, if the width of the paper is less than the width of the channel 43, the remainder of the channel 43 is maintained light-tight by said liners 43a. However, said liners 43a are not a necessary part of the device.

Fig. 13 shows that the shoulder 44 of the holder 14, has a series of holes 44a; pins 44b, one of which is shown in Fig. 11, may be inserted into said holes 44a, with any desired spacing. A pair of such pins 44b therefore serves to guide the film across shoulder 44, to the guides 6, thus preventing the film from shifting laterally at shoulder 44. Each edge of the film either abuts one of said pins 44b, or is very close to a respective pin 44b. The stop-shoulder 44 is an optional feature which may be omitted, although its use is preferred. If said shoulder 44 is omitted, I can use any other type of stop for holding the holder 14 in operative position.

I claim:

1. A light-tight tank device for developing photographic film, comprising a tank which has an open top, said tank having aligned walls, said

walls being imperforate and having internal bearing recesses below said top, a spool-shaft mounted turnably in said bearing recesses, take-up spools fixed to said shaft, a pull-device, one end of said pull-device being fixed to said shaft, a light-tight cover movably seated on the top of said tank, an operating shaft which is located above the top of said tank, said cover having cover-bearings above the top of said tank in which said operating shaft is turnably mounted, means external to said cover for turning said operating shaft, means connecting said operating shaft and said spool-shaft.

2. A device for developing photographic film, comprising a tank which has an open top, a loader compartment fixed to an end-wall of said tank, said loader compartment being external to said tank and having an open top, a removable cover which is adapted to close said open top of said tank and said loader compartment, said loader compartment having a top wall which is spaced from the respective part of the bottom face of said cover when said cover is in position to close said tank, said top wall and said respective part of said bottom face of said cover being shaped to form a longitudinal exit channel for said loader compartment when said cover is in said tank-closing position, said cover closing said open top of said loader compartment save at said exit channel when said cover is in said tank-closing position, a loader which is turnably supported in said loader compartment to turn around a transverse axis, said loader having a transverse slit, said holder being shaped to receive a roll of film and protective paper, longitudinal pull means located and adapted to grip said film and to pull it longitudinally into said tank in a direction away from said exit channel and through said slit so as to simultaneously unwind said film and said protective

5

paper off said roll, said longitudinal pull means turning said loader around said transverse axis into an unwinding position, said loader having a stop which abuts the wall of said loader compartment when said loader is in said unwinding position, said slit having a transverse paper-guiding edge which is located to guide said protective paper when said paper is thus unwound from said roll and said loader is in said unwinding position, said paper-guiding edge being located substantially directly vertically below the inner end of said exit channel when said loader is in said unwinding position, said exit channel extending downwardly from its inner end to its outer end, said outer end being longitudinally further away from said tank than said inner end, said exit channel being free from sharp bends so that the paper is automatically fed through said exit channel when said roll is thus unwound.

SAMUEL FREEMAN.
